UNITED STATES PATENT OFFICE.

JOB H. RIDGWAY, OF PHILADELPHIA, PENNSYLVANIA.

WATERPROOFING PAPER.

SPECIFICATION forming part of Letters Patent No. 257,761, dated May 9, 1882.

Application filed February 13, 1882. (No model.)

To all whom it may concern:

Be it known that I, JOB H. RIDGWAY, a citizen of the United States, and a resident of Philadelphia, Pennsylvania, have invented an improvement in Waterproofing Paper, of which the following is a specification.

The object of my invention is to cheaply water-proof paper or pasteboard by applying paraffine to it in the manner described hereinafter.

Heretofore paper has been rendered water-proof by saturating it with melted paraffine; but I have found that paper can have a thin film of paraffine imparted to it by simply rubbing blocks, lumps, or granulated masses of that material on the surface of the paper.

Different appliances may be used in carrying out the process. In the diagram shown in Figure 1 of the accompanying drawings, for instance, a continuous sheet, A, of paper is drawn from a roll in the direction of the arrow over and in contact with a table or support, B, having a smooth face; or, in place of this support, a roller having journals adapted to fixed bearings may be used, as shown in Fig. 2.

A block, D, of solid paraffine is contained within a suitable receptacle, E; or there may be a number of slabs or a powdered or granulated mass of paraffine in the said receptacle, in which a weight or number of weights fit freely, so as to force the paraffine down onto the paper with a constant pressure. The paraffine has such an affinity for the paper that the surface of the latter will be coated with a thin adhesive film of that material.

The coated paper may, if desired, be passed between pressure-rollers.

When paper in sheets has to be coated appliances for passing the paraffine under pressure over the surface of the stationary sheets may be used. It should be here understood,

however, that I neither claim nor restrict myself to any specific mechanism or apparatus wherewith to facilitate the coating of the paper.

While the paper thus prepared may not be so permanently water-proof as paper saturated with molten paraffine, it is well adapted for use in connection with interior work, such as for lining refrigerating structures. The prepared paper, moreover, is less than half the cost of the saturated paper, for a very thin film only of paraffine is imparted to the surface. Both sides of paper may be treated in the manner described.

I am aware that paraffine has been applied to fabrics for rendering the same water-proof, but always under the influence of such heat as to impregnate the fabric with that substance; but in my invention no heat is used, the solid paraffine being applied to the paper while both are cold, and the paper having a thin film of paraffine imparted to the surface only.

I claim as my invention—

1. The mode herein described of imparting a coating of paraffine to the surface of paper or pasteboard, the said mode consisting in applying a block or blocks or granulated or powdered masses of paraffine to the surface of the paper under pressure while the paper or the paraffine is in motion, substantially as described.

2. As an article of manufacture, paper or pasteboard having on one or both faces a thin film of paraffine, as set forth.

In testimony whereof I have signed my name to this specification in the presence of two subscribing witnesses.

JOB H. RIDGWAY.
